United States Patent Office

Des. 192,596
Patented Apr. 17, 1962

192,596

BALL TYPE CASTER

Albert E. Rice and Ford A. Rice, both of
945 Leader Bldg., Cleveland, Ohio

Filed Apr. 11, 1960, Ser. No. 60,144

Term of patent 14 years

(Cl. D10—6)

FIG. 1 is a front elevational view of a ball type caster showing our new design;

FIG. 2 is a side elevational view;

FIG. 3 is a perspective view;

FIG. 4 is a bottom view; and

FIG. 5 is a top plan view thereof.

We claim:

The ornamental design for a ball type caster, as shown.
